UNITED STATES PATENT OFFICE.

ANTHONY J. PIESZAK, OF DUNKIRK, NEW YORK.

DEVICE FOR REMOVING, REPLACING, AND ADJUSTING STUFFING-BOX MECHANISM FOR VALVES.

1,086,728.

Specification of Letters Patent.

Patented Feb. 10, 1914.

Application filed February 13, 1913. Serial No. 748,150.

To all whom it may concern:

Be it known that I, ANTHONY J. PIESZAK, a citizen of the United States, residing at Dunkirk, in the county of Chautauqua and State of New York, have invented certain new and useful Improvements in Devices for Removing, Replacing, and Adjusting Stuffing-Box Mechanism for Valves; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

My invention relates to mechanism for removing, re-placing and adjusting stuffing-box mechanisms on shut-off-valves located under ground, and has for its object the construction of an instrument adapted to be inserted into the valve-tube to engage the stuffing-box mechanism of a valve, to engage and remove the wrench-head on the upper end of the valve-stem, and to unscrew and remove said wrench-head and stuffing-box mechanism from the valve-stem and lift the same out of the valve-tube when the stuffing-box mechanism can be re-packed and re-placed upon the valve.

The features of my invention are herein-after set forth and pointed out and are illustrated in the accompanying drawings in which,

Figure 1, is a vertical central section of a valve-tube in place upon a valve, showing my invention in vertical central section therein, ready to be operated. Fig. 2, is a like view showing my invention therein in operation, with the stuffing-box mechanism partially lifted upward. Fig. 3, is a vertical central section of my invention, removed from the valve-tube, and with the stuffing-box mechanism removed from the lower end thereof. Fig. 4, is a transverse central section of the stuffing-box mechanism of a shut-off-valve removed from said valve, the parts thereof being separated for the purpose of re-packing, and having a mandrel in place therein. Fig. 5, is a plan view looking upward, of the lower end of my invention. Fig. 6, is a view in elevation of one part thereof. Fig. 7, is an end view in

elevation, looking upward, of a portion of my invention.

55

As is well known, the common practice in laying water-mains in cities, shut-off-valves of certain sizes, usually the smaller sizes, are placed in the mains under ground, with tubes leading upwardly from said valves to the surface, said tubes being for the purpose of permitting the insertion of a key or wrench to open and close said valve. It frequently happens, however, that it becomes necessary, owing to leaks around the valve-stem, to re-pack the stuffing-box, and adjust the same so that there shall be no leak around the valve-stem. In such a case, it is the present practice to dig the earth out, making an opening down to the valve, 70 so that a workman can get thereto, and re-pack the valve. My invention is designed to overcome this difficulty and enable the workman to remove the stuffing-box from the valve and lift it upward in the valve-tube and re-pack the same outside of the tube and then re-place it in a re-packed condition, upon the valve and after the same has been re-placed, to adjust the stuffing-box, and re-place the wrench-head 80 upon, and secure the same to the valve-stem.

75

In these drawings A, indicates a shut-off-valve in the water-main, A', indicates the stuffing-box mechanism thereof, a, indicates the flange on the lower portion of the stuffing-box mechanism, preferably made hexagonal, adapted to receive a wrench or other tool thereabout, by means of which said stuffing-box may be screwed or unscrewed 90 into or out of the housing of the valve A.

a', indicates the flange on the upper part of the stuffing-box, which is preferably made hexagonal, and preferably of equal size with the flange a, so as to be engaged and operated with the same tool which operates the flange a.

A², indicates the valve-stem, A³, indicates a wrench-head, which is secured upon the upper end of the valve-stem A², by means 100 of a screw-nut A⁴, which is placed upon the upper end of the valve-stem above the wrench-head. The screw-nut A⁴, has its lower corners, or corner edges, beveled off as shown in Figs. 1, 2, and 3, for the purpose hereinafter described.

105

A⁵, indicates the valve-tube, which leads from the location of the valve under ground, to the surface, and through which tube access to the valve may be had for the purpose 5 of opening or closing the same.

In carrying out my invention, I provide a tool having the lower end B, thereof, chambered out to receive the flanges a, and a', of the stuffing-box mechanism A', and 10 the stem B', of this tool, is tubular and terminates at the upper end in handle mechanism b. The stem B', being of such length as may be desired, and which may be required by the particular locality. From the 15 upper end, thereof, and pivoted in the handle mechanism b, a pair of rods B², extend downwardly to, and are journaled in the lower end B, of this tool, the lower end b', of these rods being bent at right angles to 20 the upright portion thereof and extending inwardly toward the stuffing-box body A', underneath one of the flanges a, or a', the upper ends of said rods B², being provided with operating handles b², by means of 25 which the rods B², can be operated to turn their lower ends b', inward so as to engage the under side of the flange a, as shown in Figs. 1, and 2, for the purpose of retaining the stuffing-box mechanism A', 30 within the lower end B. Within the tubular stem B', I place a wrench-head removing tool C, the lower end of which is chambered out to fit and receive the wrench-head A³, on the valve-stem. This tool C, is provided with 35 a tubular stem C', which extends upwardly within the tube B', and terminates in handle mechanism c, at the upper end thereof. From the upper end of this tube C', and journaled in the handle mechanism c, there- 40 on, are rods C², which extend downwardly to and are journaled in the part C, and the lower ends c', of the rods C², are bent at right angles to the upright portions thereof and extend inwardly toward the valve-stem 45 A², (see Figs. 1 and 2) sufficiently to engage the under side of the wrench-head A³. The upper ends of the rods C², are provided with handles c², by means of which the rods C², may be operated to turn the lower ends c', 50 thereof, outwardly from under the wrench- head A³.

For removing the nut A⁴, I provide a key-rod D, having on the lower end thereof a nut-receiving-member D'. This key-rod D, 55 extends upwardly through the tube C', and is provided on the upper end thereof with a handle D². In order to retain the nut A⁴, within the nut-receiving-member D', there is journaled in the nut-receiving-member 60 D', a rod E, the lower end e, of which is bent slightly so that it will engage the beveled corner on the lower side of the nut A⁴, and the opposite side of the cham- ber in the member D', has a bead d at the 65 lower edge thereof adapted to engage the

bevel on the nut A⁴, opposite to the lower end e, of the rod E. The rod E, extends upwardly through the tube C', and is pro- 70 vided on its upper end with a handle e', by means of which the rod E, may be turned so that the lower end e, thereof, will engage or release the nut A⁴, as may be desired. In order to center the rod D, and retain the same within the tube C', I place upon the rod D, adjacent to the upper and lower ends 75 thereof disks F, shown in Fig. 6, which are split into two portions and are secured upon the rod D, by means of a screw, shown by broken lines in Fig. 6, which will clamp the same firmly upon the rod D. The opening f, for the rod D, being of proper diameter to firmly clamp the rod D, while the opening f', for the rod E, is large enough to permit the rod E, to rotate freely therein, the disks F, being adapted to rotate freely within 80 the tube C'. While I have shown my im- 85 proved stuffing-box adjusting mechanism as adapted for use upon hexagonal flanges, a, and a', it is obvious that the same could be formed to fit and operate upon flanges hav- 90 ing different formations than shown in these drawings.

In operation, when it is desired to remove and re-pack a stuffing-box from an under- 95 ground valve, my improved tool is lowered downward in the valve-tube A⁵, until the same has engaged the flanges a, and a', of the stuffing-box A', when the handles b², on the rods B², are turned as shown in Fig. 1, so that the lower ends of the rod B², will 100 engage the under side of the flange a. The part C, will have embraced the wrench- 105 head A³, and the handles c², are turned as shown in Fig. 1 so that the lower ends c', of the rods C², will extend under and engage the under side of the wrench-head A³. The key-rod D, is then pushed downward until the member D', embraces the nut A⁴, when the handle e, is operated to turn the lower end e, of the rod E, to engage the beveled 110 corner of the nut A⁴, and securely clamp it within the member D'. The handle D², is now operated to unscrew the nut A⁴. The handles c', are now operated and raised upward to lift the wrench head A³, upwardly 115 off of the valve stem as shown in Fig. 2. The nut A⁴, and the wrench-head A³, being respectively retained in the members D', and C, until released as hereinafter described. The handles b, are now revolved to unscrew 120 the stuffing-box mechanism from the valve- housing A, which is then lifted upwardly to draw the stuffing-box mechanism A', off of the valve-stem A², as shown in Fig. 2. When the stuffing-box is moved upwardly 125 clear of the valve-stem A², the tool B, and B', is raised upwardly out of the valve- tube A⁵, carrying with it the members C, and B', and the wrench-head A³, and A⁴, retained in said members. When the stuff- 130

ing-box is raised out of the tube A⁵, it may be removed from the member B, by turning the lower end b', of the rod B², backward. The stuffing-box may then be taken apart, as shown in Fig. 4, and the old wornout packing removed from the lower half thereof, when a mandrel G, of the same diameter as the valve-stem is placed through the upper portion a', through the gland a², and through the lower portion a. Packing, a³, shown in broken lines in Fig. 4, is then wrapped about the mandrel G, within the lower portion a, until sufficient packing is placed therein, when the gland a², is moved up against the packing in the lower part a, and the upper part a', is again screwed in place upon the lower part a. The mandrel G, is then removed, and the stuffing-box again replaced within the member B, and the lower ends b', of the rods B², are turned inward to retain the stuffing-box mechanism A, within the member B. The apparatus is then picked up bodily by the workman and lowered into the tube A⁵, and when the stuffing-box has been carefully placed upon the valve-stem A², and screwed down tightly into the valve-housing A, the member C, is operated to place the wrench-head A³, upon the upper end of the valve-stem A², and the handles c², are turned to move the lower ends of the rods C², backward from under the wrench-head A³, the key-rod D, is pushed downwardly and revolved by the handle D², to again place the nut A⁴, upon the valve-stem. The handle e', is now operated to cause the lower end e, of the rod E, to release the nut A⁴. The handles b², on the upper end of the rod B², are now operated to turn the lower ends of the rod B² out of engagement with the under side of the flange a, when the apparatus is raised upward slightly, and the handle b², turned again to the position shown in the Fig. 1, so that the lower ends of the rod B², will rest upon the upper side of the flange a, and thereby support the member B, out of engagement with the lower flange a. The handles b, are now operated to adjust the upper half a', of the stuffing-box mechanism by screwing the same downward to compress the packing within the stuffing-box about the valve-stem A². When this has been accomplished the handles b², are again operated to turn the lower ends b', of the rods B², outwardly so that the apparatus may be raised upwardly and out of the tube A⁵.

I am thus enabled to re-pack a stuffing-box for an under ground shut-off valve, without the necessity of digging the earth away from around it.

Having thus fully described my invention, what I claim as new and desire to secure by Letters-Patent is,

65 1. In an apparatus of the character de-

scribed, a member adapted to engage a stuffing-box, unscrew it from a valve-housing, and to re-screw it thereinto, a stem secured to said member of such length as may be desired, handles on the upper end of said stem, rods pivoted at the upper end of said stem and in the member on the lower end thereof having their lower ends bent at right angles to the upright portion of said rods, and handles on the upper ends of said rods, substantially as and for the purpose set forth. 75

2. In an apparatus of the character described, a member adapted to embrace and turn a stuffing-box mechanism, a tubular stem leading upward therefrom, handles on the upper end of said stem, mechanism adapted to lock a stuffing-box mechanism within said member, and release the same when desired, a member within said tubular stem, and guided thereby to embrace the wrench-head on the upper end of a valve-stem, means in said second member adapted to lock said wrench-head therein, and release the same when desired, a nut-turning key mounted within the tubular stem last mentioned and guided thereby to engage a nut on the upper end of a valve-stem, and means in said nut-turning key adapted to lock a nut therewith and release the same when desired, substantially as and for the purpose 95 set forth. 90

3. In an apparatus of the character described, a member adapted to engage and rotate the flanges of a valve-stuffing-box, a tubular stem extending upwardly therefrom, means on the upper end of said tubular stem for operating the same, rods journaled to the upper end of said tubular stem and in the member at the lower end thereof, means to rotate said rods, an angular extension on the lower ends of said rods adapted to extend inwardly under one of the stuffing-box flanges to prevent the same from falling out of said member, another member within said tubular stem guided by and adapted to embrace the wrench-head on the upper end of a valve-stem, a tubular stem extending upwardly from said last mentioned member within the first mentioned tubular stem, means on the upper end of said last mentioned tubular 110 stem for lifting and rotating the same, rods journaled to the upper end of said last mentioned tubular stem and extending downwardly to and journaled in the last mentioned member, angular extensions on the lower ends of said rods adapted to lock a wrench-head within said last mentioned member, means on the upper ends of said rods to rotate the same, a nut embracing member within said last mentioned member, 115

a key-rod secured in said nut embracing member and extending upwardly therefrom, disks secured on said key-rod and rotatable within said last mentioned tubular stem whereby said nut embracing member is 130

guided down over a nut on the upper end of a valve-stem, a rod journaled in said disks and in said nut embracing member, an angular extension on the lower end of said rod adapted to engage a nut, a bead in the opposite wall of said nut embracing member adapted to engage the lower corners of a nut, and means on the upper end of said last men-

tioned rod for rotating the same, substantially as and for the purpose set forth. 10

In testimony whereof I affix my signature, in presence of two witnesses.

ANTHONY J. PIESZAK.
